INK PAD

Claude H. Bright, Memphis, Tenn.

Application February 25, 1937, Serial No. 127,641

2 Claims. (Cl. 101—125)

This invention relates to improvements in ink-pads and particularly to a double-faced pad adapted to have its opposite ink faces treated with different inks and to means by which such a pad may be supported to expose either of its faces for use and be adapted for ready reversal to bring the other face into position for use.

The objects of the present invention are:

To make a pad and supporting means therefor, one face of which pad is adapted to receive and retain available for use, ink as of that type which is used in connection with the ordinary rubber hand stamp and the opposite face of which pad is adapted to retain an entirely different class of ink, such as that which is used in making copies from a waxed stencil.

A further object of the invention is to support such a pad, in such manner that it not only may be easily reversed, but that in either of its positions the unused face will be supported out of contact with surfaces which, were they allowed to come in contact with the pad, would hold and transfer the ink so held to the opposite face of the pad upon reversal.

The means by which these and other objects are accomplished and the manner of their accomplishment, will readily be understood from the following description, on reference to the accompanying drawing, in which,—

Fig. 1 is a perspective view of the pad with the forward side of the supporting case and the forward side of the pad frame, cut away to display the edge of the pad.

In Fig. 2 is an enlarged fragmentary section taken on the line II—II of Fig. 1, showing the stamp-inked face of the pad turned upward.

Fig. 3 is a side elevation of the pad with the front side of the supporting case cut away and showing the stencil face of the pad turned upward, and the manner of using a roller therewith.

Fig. 4 is a fragmentary side elevation of the pad as in Fig. 3, but showing a sheet of thin paper being contacted therewith by a brush.

Referring now to the drawing in which the various parts are indicated by numerals, the supporting case is a shallow rectangular tray, having ends 10 and sides 11, the forward one of these sides having been cut away in all the views, and a bottom 12 which may be directly turned upward to form the ends and sides as indicated in Figs. 2 and 3, or as shown in Fig. 1, may be joined to these ends, and/or sides through a re-entrant fillet 13, which fillet in such case would form ledges to support the ends or the sides of the pad, or which may entirely encircle the case and form

a support therearound for both ends and sides of the pad.

In Figs. 2 and 3 supporting members 14 are disposed in the tray and accomplish an equivalent support for the pad.

The pad comprises a body member 15 made of wood or some other rigid material, to one face of which is secured a thick ink-absorbent layer 16 as of felt, the felt being held in place by a covering of cloth 17 which is preferably wrapped around the felt 16 and the body member 15, and secured along one edge of the member as by staples 17A. Secured against the body member opposite the felt pad is a sheet of non-absorbent material 18, which sheet preferably has a flat rigid exterior surface. The outer face of the sheet 18 is in turn covered by a somewhat heavier ink absorbent cloth 19. The pad thus formed is surrounded by a frame of thin metal, composed of two halves 20—21, which are preferably hinged together at one end as by a hinge 22. Opposite the hinge, the ends 23, 24, of these frames are made deeper so that they over-lap and are secured together and to the body member 15 of the pad by a thumb screw 25, this screw serving as a button or short handle for removing the pad. The remote edges of these frame halves are inwardly turned to form flanges 26, 27 respectively, the flange 26 overlying the peripheral edge of the sheet 18, and holding the cloth 19 thereagainst. The flange 27 on the opposite frame half 21, rests directly against the cloth covering of the felt layer 16 and preferably is so tightly held thereagainst when closed that the general surface of this felt layer and its cloth covering is above the surface of the flange. One of the ends 10 of the tray is provided with a notch or slot 30 adapted to receive the thumb screw 25 and permit the pad frame to rest on the support 13 or 14 as the case may be. Either of these supports holds the inked face of the pad which is downward, clear from, and out of contact with the bottom 12 of the tray.

In using the device the pad is placed in the tray with the desired ink surface upward. As shown in Figs. 1 and 2 the felt layer is upwardly turned and the pad when this layer is impregnated with the proper ink is available for use with the ordinary rubber stamp. If it is desired to use the opposite face, the pad is lifted out of the tray, the screw 25 serving as a handle, and the opposite face turned upward. The cloth 19 covering this face is properly impregnated with an ink suitable for stencil work. A stencil 31 is cut and laid in usual manner on this inked cloth. Preferably the

hinged end of the pad is raised out of the tray and an end 32 of the stencil is turned over the hinged end, and the hinged end of the pad is pushed down into the tray to secure such folded under end of the stencil. If the copy is to be reproduced on a comparatively stiff or thick paper such as a postal card, such card 33 is laid on the stencil and a roller 34 having a handle 35 is pulled along the surface of the paper to contact it against the stencil, the movement of the roller preferably being away from the under-folded edge of the stencil so that the stencil is firmly held during such movement. The copy so made is quickly removed and additional cards are successively put in place, 10 similarly treated, and removed. Where letter paper or other thin paper is used, a sheet 36 of paper is laid on the pad (Fig. 4) and pressed against the pad by a brush 37, subsequent procedure being as before.

20 It will be understood that while the preferred construction involves dissimilar faces for the pad, it will be possible to make this pad with two ink absorbing felt layers as for use with a red and a black ink for rubber stamps, or with two stencil 25 surfaces as for use with stencil inks of two colors.

What I claim is:

1. In combination, a tray, a removable pad disposed therein, and a removable stencil covering

for said pad, said pad having at least one surface adapted to co-operate with said stencil when in use, said stencil having a length, in excess of the length of said pad and having one end portion wrapped around and under one end of said pad, 5 said tray having transversely disposed ledges at its opposite ends adapted to support said pad and to engage and secure said under-turned stencil portion thereagainst, said engagement forming the sole means of securing said stencil against creep 10 along said pad.

2. In combination, a tray, a removable pad disposed therein, said pad having a handle member projecting from one end, and a removable stencil covering for said pad, said pad having at least one 15 surface adjacent to co-operate with said stencil for use, said stencil having a length in excess of the length of said pad and having an end portion disposed around and under the end of said pad, opposite said handle end, said tray having transversely disposed ledges at its opposite ends adapted to support said pad and to engage and secure said under-turned stencil end portion 20 thereagainst, said engagement forming the sole means of securing said stencil against creep along 25 said pad.

CLAUDE H. BRIGHT.
